HANGER FOR BOOTS OR THE LIKE

George J. Ducharme, 3731 Griffith View Drive,
Los Angeles, Calif. 90039

Filed Apr. 10, 1967, Ser. No. 6,601

Term of patent 7 years

(Cl. D54—1)

FIG. 1

FIGURE 1 is a perspective view of a hanger for boots or the like, the broken lines of one hanger, a pair of boots and a pole being for illustrative purposes only;

I claim:

The ornamental design for a hanger for boots or the like, substantially as shown and described.
